UNITED STATES PATENT OFFICE.

ADELBERT EUGENE HALL, OF WEST BAY CITY, MICHIGAN.

RECOIL-OPERATED FIREARM.

No. 830,226.

Specification of Letters Patent.

Patented Sept. 4, 1906.

Application filed March 14, 1903. Serial No. 147,868.

To all whom it may concern:

Be it known that I, ADELBERT EUGENE HALL, a citizen of the United States, and a resident of West Bay City, in the county of Bay and State of Michigan, have invented 5 certain new and useful Improvements in Recoil-Operated Firearms, of which the following is a specification.

This invention is a recoil-operated firearm; 10 and the improvements consist in certain combinations of devices and the equivalents thereof, as will be fully set forth in the specifications, having for their object to automatically eject a shell upon the discharge of 15 the gun and to automatically load the gun by putting a new shell into place.

The invention also provides means for governing the speed of the recoil of the discharged shell and the speed with which the fresh shell 20 is pushed into place.

Reference is had to the accompanying drawings, in which—

Figure 1 is a longitudinal section, broken away in parts, showing a gun with my improvements attached; the parts being shown 25 in the position that they occupy at the instant of firing or just as the hammer strikes the firing-pin. Fig. 2 is a similar section showing the parts in the position they occupy 30 near the end of the recoil. Fig. 3 is a vertical section on the line $x-x$ of Fig. 2 looking toward the butt of the gun, and Fig. 4 is a similar section taken on the line $x'-x'$ of Fig. 2. Fig. 5 is a top plan view showing the bolt and 35 the spiral rods and governors that control its recoil. Figs. 6 and 6^a are detail views, on an enlarged scale, showing the operation of the catch K. Fig. 7 is a detail perspective view of the lever 25.

As is clearly shown in the drawings, the 40 device consists in a mechanism carried by the stationary stock A and lower casing A', of sheet metal, that incloses the mechanism, and the forward part of the stock A'', upon which 45 the barrel B is mounted, so as to have a limited back-and-forth sliding movement. Fixed to the barrel B and slidable with it is the slotted upper casing C, of sheet metal. The upper casing C is slidably mounted on the lower 50 casing A' by means of flanged guides 1 and 1', as shown in Fig. 4, or any other suitable manner. Fixed to the rear end of the barrel is a ring B', in the lower end of which is journaled a pair of revoluble oppositely-threaded 55 screws G and G'. The rear ends of the screws

G and G' are supported by the bracket T; fixed to the upper slidable casing C. It is thus seen that the barrel, the casing C, and the revoluble screws G and G' all have a limited back-and-forth movement relatively to 60 the stationary parts A A' A''.

A rearwardly-extending hollow bolt D is mounted upon the two screws G and G' by means of internally-threaded bearings D' and D', that engage the threads of the screws 65 G and G', respectively. Moving the bolt D back and forth, as indicated in Figs. 1 and 2, revolves the screws G and G' in opposite directions. In practice the backward movement of the bolt D is caused by the recoil of 70 the shell in firing, and the forward movement is imparted by a compressible spring E, bearing against the bolt D at one end and against the abutment I at the other end. The abutment I is stationary, being preferably formed 75 integral with the stock A, as shown in Figs. 1 and 2.

The firing-pin F passes through the spring E and through the bolt D in line with the axis of the bore. Its head F' prevents its being 80 forced back through the bolt D by the shock of recoil, and the head F' is held against the bolt by the pressure of the shell so as to move rearwardly with said bolt. In fact, the force 85 of recoil is exerted against the head of the pin, which being larger than the aperture in the forward end of the bolt through which pin passes, is precluded from disengagement with the bolt.

If the bolt D and spring E were arranged 90 to yield the instant the discharge occurred, the velocity of the bullet, and consequently the efficiency of the firearm, would be diminished. I therefore have devised means for preventing any drawing back of the bolt D 95 relatively to the barrel B until after the greatest part of the force of recoil is spent, and I utilize only the remainder of the force of the recoil for throwing out the discharged cartridge and inserting the new one. I use for 100 this purpose certain locking devices which lock the bolt D to the barrel until after the explosion takes place and then release it, and also a governing device to prevent too rapid recoil of the bolt D. 105

The locking device is illustrated in Figs. 1 and 2. It consists, first, in the means for preventing rotation of the screws G and G', comprising outwardly-extending wings N', rigidly fixed to the screws G and G' and 110

adapted to engage a projection P, formed integral with the fixed casing A', whereby the wings N' and the screws G and G' are held against rotation when the slide barrel B, the upper casing C, and the bracket T are in their forward position, as shown in Fig. 1. At the instant of firing the shock of recoil acts against the bolt D, tending to revolve the screws G and G', but is prevented from doing so by the engagement of the wings N' with the projection P. The force of recoil is thus exerted against the bracket T, which being integral with the upper casing C and barrel B shoves them back a short distance into the position shown in Fig. 2. This releases the wings N' and permits the screws G and G' to revolve under the remaining action of the recoil and permitting the bolt D to move back, as shown in Fig. 2, compressing the spring E and drawing the cartridge out of the barrel by means of the extractor S.

J is an ejector-pin carried by the bolt D and adapted to operate in the usual way to tilt the empty shell out of the slot in the movable casing C, as shown in Fig. 2. For convenience in illustrating I have shown the shell tipped up (see Fig. 2) by the ejector-pin, although the bolt D is not at the end of its stroke. I have done this for the sake of clearness in the drawings; but it will be understood that the ejector-pin J does not in practice tilt the shell out until the end of the pin J strikes the abutment I.

A governor is provided on each screw G and G' to prevent their too rapid rotation and to control the recoil of the bolt D. Each governor consists, as shown in Figs. 1, 2, and 3, of a pair of fly-balls, preferably slotted to receive the wings N', which thus serves as guides to the balls while revolving. The balls are mounted on pivotal levers carried by the screws G and G', as shown in Figs. 1, 2, and 3, and when the balls fly out under the revolving action of the screws their inner ends N'' press against the end of a stationary rod W, secured at one end to the ring B' and passing loosely through each of the hollow screws G and G'. The effect of the pressure of the ends N'' against the rods W is to force the screws G G' back. Each screw has at its back end a friction-cone Y, formed integral with the screw and fitting in a conical recess Y' of the bracket T. When the screws G or G' are forced back, as just described, the revolving cone Y acts as a friction-brake to further retard the whirling motion of the screws. I adjust the frictional effect of each cone Y by means of the double-leaf springs V, which press against the points of the cones on one side and having their pressure regulated by the pressure-adjusting screws H on the other side, the double-leaf springs and screws both being mounted in the bracket T, as shown in Figs. 1 and 2.

65 When the bolt D is in the position shown

in Fig. 1, it is further locked against recoil by the catch K, which is pivoted to and carried by the bracket T. At the first instant of recoil shock the rear end of the bolt D, which is preferably formed of a cylindrical tube D'', is prevented from moving back by the upwardly-projecting pivoted end of the catch K, but immediately thereafter the barrel B, upper casing C, bracket T, and screws G and G' move bodily backward a short distance, 75 as previously described, sufficient to permit the latch to assume the horizontal position shown in Fig. 2, thus releasing the lower end of the catch K from its retaining-hook and permitting the catch to tilt up to the position shown in Fig. 2, allowing the tube D'' to pass over it. A hook K' is mounted on a suitable upwardly-projecting arm K'', carried by the lower casing A' between the screws G and G'. In the horizontal position of the catch K 85 (shown in Figs. 2 and 6a) its end bears against the upper end of the arm K'' and locks the bracket T, the upper casing C, and the barrel B in their recoil position and keeps them so locked until the spring E has forced the tube 90 D'' forward again and permitted it to release the upper end of the catch K, so that K may drop down into the position shown in Figs. 1 and 6. The upper end of the arm K'' is beveled or inclined on that face adjacent the 95 free end of the catch, which catch is similarly beveled, the purpose of which is to permit the beveled end of the catch to slip off of the beveled or inclined face of the arm, such incline directing the arm toward the position 100 which it occupies in Fig. 1. As soon as the catch slips downward somewhat it will have moved out of alignment with the movable portion T of the frame and the upper end of the arm K'' and permit the parts to assume 105 the position shown in Fig. 1. Obviously, however, the latch cannot move out of its horizontal position until the bolt has moved forward sufficiently to clear the latch.

I have not illustrated in detail the mechanism by which the new cartridge may be fed from the lower part of the casing A' up into line with the barrel so that the bolt D may force it into the barrel, as such constructions are old and well known, and any suitable device 110 may be used for the purpose, although I prefer to employ the usual laminated spring Z, upon which the cartridges rest and by which they are fed up to the chamber, as indicated in Fig. 4.

The hammer R is automatically cocked by the firing-pin F when it is pushed back by the recoil of the bolt D, as previously described. I also provide means for preventing the release of the hammer by the trigger 115 when the parts are in their recoiled positions. (Shown in Fig. 2.) As one embodiment of such means I have shown a lever 25, pivoted intermediate its ends in a slot 26, formed in that portion of the stationary frame A' lying 120

between the recoil-bracket T and the hammer R. The forward end of the lever lies beneath the bracket T and is preferably provided with a projecting cam-like protuberance 27, which may be engaged by a projection depending from the bracket—as the spring V, for instance. The rear end of this lever is weighted and lies adjacent the upper curved tooth of the trigger. When in normal position, such as shown in Fig. 1, the rear end of the lever lies above the tooth 28 of the trigger, being held in such position by the engagement of the projection on the bracket T with the cam-like protuberance on the forward end of the lever. When the bracket moves rearwardly by the force of the recoil, the forward end of the lever is released and moves upwardly, owing to the weighted rear end of the lever, which drops down opposite and in engagement, or practically so, with the tooth 28 of the trigger, which has engaged the tooth 29 of the hammer, the lever when in this position preventing the disengagement of the teeth 28 and 29.

25 What I claim as my invention, and desire to secure by Letters Patent, is as follows:

1. In a firearm the combination with the stock and fixed lower casing; of the barrel and upper casing secured thereto and slidably mounted on the lower casing; a spring-pressed bolt having a firing-pin; a pair of revoluble screws extending through correspondingly threaded sockets carried by said bolt; a governor attached to each screw; a 30 conical end on each screw and a seat for said conical end, carried by the upper casing; means operated by said governor for bringing said conical end into frictional contact with said seat, substantially as described.

40 2. In a firearm of the class described a recoil-operated bolt; a pair of revoluble screws extending through correspondingly-threaded sockets carried by said bolt and adapted to be revolved by the forward and backward movement of said bolt; together with a friction-operated device for checking the speed of revolution of said screws, substantially as described.

45 3. In a firearm having a recoil-operated bolt and screws revolved thereby; means for controlling the speed of revolution of said screws; said means comprising centrifugal governor-balls operating to force the ends of said screws into engagement with a frictional surface carried by said frame; substantially as described.

55 4. A firearm comprising in combination with the revoluble screws and the spring-pressed bolt having correspondingly-threaded sockets to receive said screws; a pair of outwardly-extending wings fixed to each screw; a fixed projection carried by the frame of the firearm and separably engaging said wings; a slotted governor-ball slidably

engaging each wing; a pivotal connection between said governor-balls and said screws; and means carried by said governor-balls for imparting longitudinal movement to said screws, substantially as and for the purpose set forth.

5 70 5. In a firearm having a recoil-operated bolt and screws actuated thereby; governors mounted on said screws; said screws automatically controlling both the forward and backward speed of the bolt, substantially as described and for the purposes set forth.

10 75 6. In a firearm of the class described having revolvably-mounted screws; and a bolt having correspondingly-threaded sockets to receive said screws; radially-extending wings fixed to said screws and adapted to engage a projection located on the frame of the firearm, whereby the screws may be locked against rotation when they are slid forward into the normal position of firing, substantially as described.

15 80 7. In a firearm of the class described, the combination with the revoluble screws capable of slight longitudinal movement; and a bolt having correspondingly-threaded sockets to receive said screws; a governor having pivotal connection with said screws and adapted to move them longitudinally, a barrel-extension bracket; a V-shaped spring located on the barrel-extension bracket in contact with the end of each screw; and means for adjusting the tension of said spring to resist the end thrust of the screw, substantially as described.

20 85 8. In a firearm the combination with a barrel, a bolt and a firing-pin, of rotatably-supported screws, a friction-brake connected with said screws, the bolt connected with the screws whereby to reduce the speed of recoil of the bolt and means for returning the bolt to normal or firing position.

25 90 9. A firearm comprising a stationary frame, a barrel movably supported thereon, a casing carried by the barrel, a bolt and firing-pin, longitudinally-moving screws connected with the bolt and rotated by the movement thereof and wings carried by the screws and adapted to temporarily engage the stationary casing for preventing the instant recoil of the bolt upon the discharge of the firearm.

30 95 10. A firearm comprising a stationary frame, a barrel movably connected therewith, a casing connected to the barrel, rotatably-supported screws, a bolt, means connecting the bolt and screws and means carried by the screws and engaging the stationary frame to temporarily prevent the rotation of the screws.

35 110 11. A firearm comprising a stationary frame, a connected casing and barrel slidably mounted upon the frame, screws journaled in the casing, a bolt carried by the screws

and wings carried by the screws and adapted to engage the stationary frame to prevent the rotation of the screws.

12. A recoil-operated firearm comprising a stationary frame, a slideable barrel and casing mounted thereon, hollow retarding means suitably journaled in the casing, pins carried by the barrel and extending through the retarding means, governors secured to and rotating with the retarding means, the governors adapted to exert the force of the recoil against the barrel through the pins and a breech-bolt carried by the retarding means.

13. A recoil-operated firearm comprising a bolt, a rotary retarding means engaged by the bolt, and a braking means carried by the retarding means and automatically operating according to the force of the recoil.

14. A recoil-operated firearm, comprising a bolt, a speed-reducing rotary means engaged by the bolt, a braking means carried by the first-named means and means for adjusting the strength of the braking means.

15. A recoil-operated firearm comprising a frame, a movable bolt, a rotary screw connected therewith and actuated thereby, the bolt moving relative to the screw, and a centrifugal governor carried by the screw and

adapted by its engagement with the frame to retard the rotation of the screw and hence the rearward movement of the bolt.

16. A recoil-operated firearm, comprising a bolt, a rotary speed-retarding means engaged thereby, a braking member carried by the first-named means, a tension device adapted to contact with the braking member and means for adjusting the tension device.

17. A recoil-operated firearm comprising a bolt, and a rotary speed-retarding member engaged thereby, one end of the member being cone-shaped and received in a similarly-shaped bearing to provide a brake.

18. A recoil-operated firearm comprising a bolt, suitably-journaled screws, a yoke carried by the bolt and sleeves formed in the yoke and engaging the screws.

19. A recoil-operated firearm comprising a bolt, suitably-journaled screws, a yoke carried by the bolt and sleeves formed in the yoke and engaging the screws.

Dated at West Bay City, Michigan,
March 2, 1903.
